UNITED STATES PATENT OFFICE.

HENRY A. BRADLEY, OF NEW YORK, N. Y., ASSIGNOR TO THE BRADLEY UNIVERSAL HEAT, LIGHT, AND POWER COMPANY, OF NEW YORK, N. Y., A CORPORATION OF NEW YORK.

HEATER FOR BOILERS AND OTHER FURNACES.

No. 799,800.

Specification of Letters Patent.

Patented Sept. 12, 1905.

Application filed December 16, 1903. Serial No. 185,373.

To all whom it may concern:

Be it known that I, HENRY A. BRADLEY, a citizen of the United States, and a resident of the borough of Manhattan, in the city, county, and State of New York, have invented certain new and useful Improvements in Heaters for Boilers and other Furnaces, of which the following is a specification.

- 10 My invention relates to that form of heater in which steam and carbonaceous material are commingled in a heated chamber and the gas resulting from their destruction and recombination of certain of their components is employed as the heating agent, its object being to provide a heater of this class which, while possessed of great simplicity and insuring of the more thorough "fixing" or union of the elements composing the gas, shall at 20 the same time be more efficient in operation than those heretofore in use and allow of a continuous operation of the parts in a given cycle when in use.

To these ends the invention consists in certain peculiarities of construction and combinations of parts, all as will hereinafter more fully appear.

In the accompanying drawing, which forms a part of this specification, I have 30 shown a side view, partly in elevation and partly in section, of one of the various embodiments of my invention, of which it is capable applied in connection with a steam-boiler and its furnace.

35 In the drawing, A indicates a boiler, and B a furnace in which the boiler is arranged and supported and which is preferably provided with an uptake b, with a suitable damper b' therein, through which the products of combustion passing upward along the uptake may be controlled and regulated.

Located in the front walls of the furnace B, below the boiler A, is a chamber C, which is preferably constructed of metal or other refractory material and is provided in its front with a suitable door c and passage-way c' and in its rear at or near its top with a passage-way or flue c². As thus constructed this chamber receives the heater D, by means of 50 which the steam and carbonaceous matter are

converted into gas and the same delivered to the furnace in an incandescent form.

This heater is preferably constructed of metal or other heat-resisting material of the required shape and size and is provided with 55 three several chambers d d' d², of which the first is the steam-chamber, the second the carbureting-chamber, and the third the fixing-chamber, with the inner walls of each provided with a series of nipples d³, projecting inward and formed with suitable orifices o in them, through which the gas that is formed in the chamber and the various components thereof are free to pass.

With the heater D constructed as above 65 described the chamber d is connected with the boiler A through the intervention of pipes a and a', while the chamber d' is connected with an oil or other carbonaceous-material-receiving tank or reservoir E through 70 the intermediary of a pipe e. As thus arranged when the heater D is heated to the required temperature and the apparatus is in operation steam from the boiler A will be admitted to the chamber d through the 75 pipes a and a', where, being superheated, it will pass under pressure through the orifices in the nipples d³ in its front wall into the carbureting-chamber d', drawing with it in 80 its passage through the heater the oil or other carbonaceous material from the tank or reservoir E through the pipe e. In its passage through the chamber d' it will be commingled with the oil or other material drawn from the tank or reservoir E, and in 85 consequence of the high degree of heat imparted to the chamber it will, with the oil or other carbonaceous material, be decomposed and the appropriate elements contained in them drawn together, forming thereby a 90 union, in which condition they will pass through the orifices in the nipples d³ in the inner walls of the chamber d' and enter the fixing-chamber d², where in consequence of the great heat possessed by this chamber the 95 union of the different elements will be more thoroughly insured and the same converted into fixed and permanent gases, which will then pass through the orifices in the nipples d³ of the inner wall of the fixing-chamber d² 100

and be discharged beneath the boiler A in the furnace B in a state of incandescence, the nipples d^3 and the orifices therein serving, in fact, as burners for the gases as they issue therefrom.

For imparting the required degree of heat to the heater D various forms of heating devices may be employed. I prefer, however, to employ a heater F of the same general form and construction as the heater D and to locate it below and slightly in front of the same. This heater F, like the heater D, is preferably constructed of metal or other heat-resisting material and of the required form and size to adapt it to the purposes for which it is intended, with its interior provided with a steam-chamber f , a carbureting-chamber f' , and a fixing-chamber f'' . As thus constructed the front walls of the respective steam, carbureting, and fixing chambers are provided with nipples f^3 , projecting from their inner walls, and are equipped therein with suitable orifices o' , through the two former of which the steam and carbonaceous material may readily pass, while through the latter, which serve as burners, the gas formed in the chamber f^2 may be discharged and burned, with the chamber f' connected with the boiler A, through the medium of which a pipe a and the chamber f'' connect with the tank or reservoir E through the pipes e and e' , as shown.

With the heater F constructed as above described its operation is substantially the same as that of the heater D, the steam from the boiler A, entering the steam-chamber f through the pipe a , becomes superheated therein in consequence of the great heat imparted to the heater F and passing through the nipples f^3 into the carbureting-chamber f' draws with it in so doing the oil or other carbonaceous material from the tank E through the pipes e and e' . In this carbureting-chamber the steam becomes decomposed with the oil or other carbonaceous material, and after a reorganization of certain of the elements of the former with certain of the elements of the latter it passes through the nipples f^3 into the fixing-chamber f'' , where the elements so joined are formed into a fixed and permanent gas, which is discharged through the nipples f^3 in the inner walls of this chamber beneath the heater D in an incandescent form, thereby enveloping this last-mentioned heater in incandescent gases and imparting to it the required degree of heat necessary to the performance of its required functions.

For imparting to this heater F the necessary degree of heat to enable it to perform its appropriate work when in operation I provide a hood or deflector H, which is located directly in its rear and is preferably supported from the walls of the chamber C,

as shown. As thus arranged the incandescent gases issuing from the orifices in the rear walls of the heater F enter this hood H with great violence and are as a consequence thereof deflected backward upon the heater itself, bathing and enveloping the same in heated gases, after which they rise and envelop the heater D, thereby not only heating the heater F to the required degree, but disposing them so that they shall contact with and envelop the heater D. In some instances this hood H may be made imperforate throughout. I prefer, however, to provide it with suitable orifices h in its inner and upper walls, as thereby the most efficient disposition of the gases issuing from the heater F for attaining the desired results is insured.

With the parts constructed and arranged as above explained and in operation the heating of the boiler or other receptacle and the production of the fuel from which it is heated are automatic and continuous. The steam from the boiler entering the steam-chambers d and f of the respective heaters D and F become superheated therein and passing on through the respective heaters draws with it in its passage through them the oil or other carbonaceous material from the tank or reservoir E, with which it is combined into a fixed and permanent gas and discharged from the heaters in an incandescent form, of which that from the heater D serves to heat the boiler A or other receptacle, while that issuing from the heater F serves to heat the heater D, as well as to heat the heater F from which it issues. While thus the operation of the parts are automatic and practically continuous when the steam in the boiler A is under sufficient pressure to cause the heaters to perform their required functions without any additional power beyond that possessed by the steam itself being required, it becomes necessary to employ other means for supplying the steam and for heating the heater F when there is no steam in the boiler or the pressure of steam is not sufficient for carrying on those operations. To allow of the heating of the heater F under these conditions, any appropriate means may be employed. I prefer, however, to adopt for this purpose a receptacle I, which may be supported within the chamber C immediately below the heater and into which may be supplied and burned oil or any other inflammable material to impart thereto the requisite heat, while to supply the steam required for operating the heaters I employ a small auxiliary boiler K. This auxiliary boiler may be of any ordinary or preferred construction and may be heated in any convenient manner. As shown in the drawing, however, it is of cylindrical form and is or may be heated by an ordinary oil-

lamp K', being provided with a safety-valve k and connected with the pipe a through the intervention of a pipe k'. While the boilers A and K are thus connected with the steam-chambers d and f and the oil or other carbonaceous-material-receiving tank are connected with the carbureting-chambers d' and f', the flow of the steam from these boilers to such chambers is regulated and controlled by the valves a², a³, a', and k², arranged in the respective pipes a, a', and k', and the flow of the oil or other carbonaceous material from the oil or other carbonaceous-material-receiving tank E is in like manner regulated and controlled by the valves e² and e³, with which the pipes e and e' are similarly provided.

The various parts being constructed and arranged as above explained, the operation of the heater will be initiated when there is no stream in the boiler or the pressure therein is not sufficient for that purpose by first closing the valves a², a³, and k² in the respective pipes a, a', and k' and then raising the steam in the auxiliary boiler K to the required pressure by means of the lamp or other heating means. Oil or other inflammable material will then be supplied to the receptacle I and ignited, and the heater F thereby heated to the required degree by its consumption. The heater F being thereby heated to the required temperature, the valve k² in the pipe k' will then be opened, when the steam will enter the steam-chamber f' and passing through into the respective carbureting and fixing chambers f' and f² will draw with it the oil or other carbonaceous material through the pipes e and e'. In thus passing through these chambers it will, with the oil or other carbonaceous material, be decomposed and converted into a fixed gas and discharged through the orifices in the nipples f³ on the rear of the heater in an incandescent form, where, being deflected backward by the hood or deflector H, it will maintain the required degree of heat in that heater and rising therefrom will envelop and heat the heater D. As soon as the heater D is thus heated to the required temperature the valve a² in the pipe a' will then be opened, when the steam will enter the steam-chamber d therein, where being superheated it will pass forward into the carbureting-chamber d' and fixing-chamber d², drawing with it the oil or other carbonaceous material through the pipe e and, being decomposed with the oil or other carbonaceous material and converted into fixed gas, will in like manner be discharged from the heater D in an incandescent form, which, with the gases discharged through the passage or flue c², will bathe and envelop the boiler, heating the water contained in it and causing the generation of steam therein. As soon as the pressure of the steam in the

boiler reaches the proper height, the valve a² 65 in the pipe a will be opened, the valve k² in the pipe k' closed, and the lamp or other heating means extinguished or withdrawn, when the operation of the parts will be thereafter continued by the steam from the boiler 70 A alone.

From the foregoing, therefore, it will be seen that I produce a heater for boiler and other furnaces in which the steam from a boiler, when the heater is applied in connection with that form of device, serves not only as the power for forcing the material composing the fuel through the heater, but forms one of the elements of such fuel and the fuel thus formed applied in turn to again 80 heat the boiler for the generation of further steam, which is again used to form and supply additional fuel, and so on in a continuous cycle so long as the furnace is in operation.

While in the foregoing I have specifically 85 described the invention as applied in connection with a boiler, it is to be understood that I do not limit myself thereto, as it is obvious that the same may be used in connection with various of the other forms of furnaces. 90

Again, while I have shown the oil or other carbonaceous-material-receiving tank E disposed beneath the furnace this is merely for illustrative purposes, and it is manifest that the same may be otherwise located without 95 in any way impairing the efficiency of the apparatus.

Having now described my invention and specified certain of the ways in which it is or may be carried into effect, I claim and desire 100 to secure by Letters Patent of the United States—

1. The combination, with a furnace, a boiler arranged therein, a plurality of heaters arranged in connection with such furnace 105 the one below the other whereby the upper one is heated by the lower one and each provided with a heat-resisting casing, inclosed communicating steam, carbureting and fixing chambers for reception, decomposition 110 and conversion of steam and carbonaceous material into a fixed gas, and with burners through which the gas formed in such heater may be discharged within the furnace for consumption therein, and a tank or reservoir 115 for receiving and storing carbonaceous material, of pipes for connecting the boiler and the tank or reservoir with both of such heaters, and a hood or deflector applied in connection with the under of such heaters, 120 substantially as described.

2. The combination, with a furnace having a chamber C arranged in the wall thereof and constructed with a passage-way or flue near its top, of a plurality of heaters arranged 125 within such chamber the one below the other, and a hood or deflector supported in said chamber for coöperation with the lower

heater, the said heaters being adapted to discharge their respective gases in lines which are substantially parallel to each other and to the under surface of the boiler, and the 5 said hood or deflector being located opposite the burners of the lower heater, substantially as described.

In testimony whereof I have hereunto set my hand this 8th day of December, 1903.

HENRY A. BRADLEY.
